DOOR KNOCKER OR THE LIKE

Walter G. Ballou, R.F.D. 2, Iron Mine Hill Road,
North Smithfield, R.I.

Filed Jan. 18, 1971, Ser. No. 107,612

Term of patent 14 years

Int. Cl. D8—09

U.S. Cl. D8—177

FIG. 1 is a front view of a door knocker or the like showing my design; and

FIG. 2 is a side elevational view thereof.

I claim:

The ornamental design for a door knocker or the like, substantially as shown.
